UNITED STATES PATENT OFFICE.

JOSEPH EDWARD CROOK, OF PROVIDENCE, RHODE ISLAND.

DESIGN FOR A COLLAR-SUPPORTER.

No. 39,939.

Specification for Design.

Patented April 20, 1909.

Application filed February 1, 1909. Serial No. 475,545. Term of patent 7 years.

To all whom it may concern:

Be it known that I, JOSEPH E. CROOK, a citizen of the United States, residing at Providence, in the county of Providence and State of Rhode Island, have invented a new, original, and ornamental Design for a Collar-Supporter or Similar Article, of which the following is a specification, reference being had to the accompanying drawings, forming part thereof.

The figure is a perspective view of a collar supporter, showing my new design.

I claim.

The ornamental design for a collar supporter or similar article, as shown.

JOSEPH EDWARD CROOK.
